PLANK OR BOARD JOINT

Frank J. Tirrel, George, Iowa

Application July 22, 1944, Serial No. 546,164

1 Claim. (Cl. 304—40)

1

My invention relates to a joint device for boards or planks.

An object of my invention is to provide a joint which is adapted to retain and securely hold the end joints between adjacently placed boards or planks.

A further object of my invention is to provide a joint of this nature which will accommodate a variety of plank sizes.

A further object of my invention is to provide a device of this character wherein more than two joints can be accommodated if desired, and to provide the device in a very simple construction, and which can be manufactured at a reasonable cost.

With these and other objects in view, my invention consists in the construction, arrangement, and combination of the various parts of my device, whereby the objects contemplated are attained, as hereinafter more fully set forth, pointed out in my claim, and illustrated in the accompanying drawing, in which:

Fig. 1 is a plan view of the joint,

Fig. 2 is a section of Fig. 1, taken along the lines 2—2 thereof,

Fig. 3 is a section corresponding to Fig. 2 showing the planks or boards in place in the joint,

Fig. 4 is a plan view of Fig. 3,

Fig. 5 is side elevation showing the planks and joints in their assembled position being supported by saw-horses, and

Fig. 6 is a side elevation showing the use of more than one joint.

My invention contemplates the provision of a simple, strong, and durable joint in which the ends of adjoining planks can be placed, and wherein the planks will then be firmly held and supported against any downward pressure. Such a joint is especially desirable when it is necessary to use a pair of boards or planks to provide a greater length, or in some cases where a few shorter pieces of board can be more conveniently carried up a stairway, and then assembled with the joints, rather than carrying up an extremely long plank around the stairway bends, etc., which in some cases is relatively impossible. My invention also contemplates the use of such a joint for those instances where only shorter planking is available, as well as other reasons.

I have used the character 10 to designate the two side pieces of the joint, preferably made of steel, although other suitable materials can be employed for the necessary strength. Attached across and to the members 10, and at the ex-

2

tremities thereof, are the upper flat straps 11 which are attached by means of welding or by any other suitable method. Attached beneath the members 10 are a pair of further straps 12 between which is provided a space 13, and hammered into the straps 12 are a series of projecting points 14. The straps 12 are equally spaced apart from the center of the arrangement.

The sides or depths 15 of the members 10 are made slightly larger than the maximum thickness of the boards or planks to be used, and will thereby accommodate planks of lesser thickness. The members 10 are of fairly substantial length, and the straps 11 include the small centrally arranged openings 16 therein.

The arrangement is used in the following manner. The planks indicated by the character 17 are placed beneath the straps 11 with their abutting ends 18 being placed over each one of the lower straps 12, with the points of abutment at 18 being centrally positioned. The arrangement is then ready for use, and it will be noted that any pressure downwardly in the direction of the arrow 19 (see Fig. 3) will be supported due to the arrangement of the straps 11 and 12 and due to the levering action therebetween.

The small projections 14 will serve to bite into the boards, thereby additionally securing the same, although I have found through actual use that the planks are otherwise firmly retained. The width between the members 10 will permit of a variety of plank widths also. If desired, nails 20 can be driven through the openings 16, into the planks for additional retention, though this is not usually necessary.

Fig. 5 shows a joint supporting a pair of planks which are supported by the horses 21, and Fig. 6 illustrates the use of two joints, accommodating three planks.

It will now be seen that I have provided all of the objects of my invention, that my invention possesses the advantages hereinabove stated, with further advantages being readily apparent.

Some changes may be made in the construction and arrangement of the parts of my invention without departing from the real spirit and purpose of my invention, and it is my intention to cover by my claim any modified forms of structure or use of mechanical equivalents which may be reasonably included within its scope.

50 I claim as my invention:

A plank joint comprising a pair of spaced side members adapted to receive plank ends therebetween, straps attached to, and beneath said side members for engagement with the ends of the

planks, further straps attached to and above said side members, and at the extremities thereof for receiving planks thereunder whereby downward pressure on the plank ends will prevent relative movement of the plank ends and will secure the same, said lower straps being spaced apart, and being attached centrally of said joint, said lower

straps including projections for engaging into the plank surfaces, said upper straps having openings for the reception of securing nails, said side members being of a depth to receive various plank thicknesses, and being spaced sufficiently to receive various plank widths.

FRANK J. TIRREL.
